AIR CONDITIONING SYSTEM AND APPARATUS

Robert A. Brand, Washington, D. C., assignor of one-half to James A. Perley, Washington, D. C.

Application April 30, 1934, Serial No. 723,251

4 Claims.

(Cl. 237—7)

Generically this invention relates to a heating unit for homes and the like, but it more particularly is directed to such a device designed to constitute an air conditioning unit.

5 One of the principal objects of this invention is the provision of a compact unit of this character constituting an air conditioning system combining a generator or heating unit, a humidifier assembly, and a fan mechanism, combined in 10 a single cabinet as a composite unit, and means for automatically controlling the various assemblies in accordance with predetermined temperature and humidity requirements.

A further important object of this invention is 15 the provision of an air conditioning system combined as a single compact unit, automatically and synchronously controlled with respect to predetermined temperature and humidity requirements, designed to eliminate the expensive and 20 excessive piping and boiler requirements heretofore necessary and at the same time reducing fuel consumption to a minimum.

Another object of this invention is the provision of an air conditioning system combined in a 25 single compact and inexpensive unit, including a generator or heating assembly comprising a unique water circulating, heat distributing and draft and fume vent systems tending to render the device noiseless and odorless in operation as 30 well as increasing the heating capacity inversely with the decrease in size of the unit; and a compact humidifier comprising a series of washer tubes and a plurality of eliminator tubes for filtering the air and providing the desired humidity; and a fan mechanism for establishing circulation 35 of the heated air, said units being automatically and synchronously controllable in accordance with predetermined temperature and humidity requirements.

40 Another object of this invention is the provision of an air conditioning apparatus of this character including a generator adapted to eliminate the use of an independent boiler heretofore necessary and to supply the necessary heating 45 requirements for a house with a minimum of water tank capacity and at the same time adapted to furnish hot water for domestic use in addition to its air conditioning requirements.

Another object of this invention is to provide 50 a unit of this character designed for the home or buildings where steam or other heat is not practicable due to lack of space for boiler or circulation conditions and having a boiler requirement of 15 gallons of water as compared with 150 to 55 200 in the systems now in use, thereby greatly reducing production and maintenance costs.

With these and other objects in view, which 60 will become apparent as the description proceeds, the invention resides in the construction, combination and arrangement of parts, hereinafter

more fully described and claimed, and illustrated in the accompanying drawings, in which like characters of reference indicate like parts throughout the several figures, of which:

Fig. 1 is a plan view of the invention with the 5 cabinet partly in section.

Fig. 2 is a side elevation of the generator partly in section.

Fig. 3 is an end view of Fig. 2.

Fig. 4 is a fragmentary detail perspective showing the arrangement of the water tubes, air outlet, and fin plates.

Fig. 5 is a detail perspective view of the water eliminator and air purifier tubes.

Fig. 6 is a detail of the air washer and humidifier tubes.

The air conditioning systems with which I am familiar have proven deficient in requiring cumbersome and costly apparatus necessitating the use of large capacity boilers, expensive piping 20 connections rendering such apparatus impractical in connection with air conditioning in buildings having limited space, the production and operating costs in many instances being prohibitive, and it was to overcome such deficiencies, 25 and to provide an air conditioning unit or apparatus including a heating unit, a combined air washer, purifier and humidifier, and an air circulating fan mechanism, so designed that the several units could form a compact unit housed 30 within a single casing or cabinet, materially reducing the water capacity of the generator unit without decreasing the heating capabilities of the unit, and having the generator, humidifier, fan 35 mechanism, and gas supply individually and collectively automatically operable in accordance with predetermined temperature and humidity requirements, that I designed the air conditioning apparatus forming the subject matter of this invention.

40 In the illustrated embodiment of this invention there is shown my improved air conditioning unit or apparatus A comprising heating unit or generator B, humidifier or scrubber and air filter C, and air circulating or fan mechanism D. Said 45 units or mechanisms B, C, and D are preferably housed in a casing or cabinet !.

Generator

The generator or heating mechanism B comprises, in the present instance, a rectangular fire box and supporting base 2, the bottom of which is formed of or lined with an insulating material 3. Mounted substantially central of said fire box 2 is a tubular (in the present instance) gas burner 4 with one end supported on bracket 5 bolted or otherwise suitably secured to end wall 6 and the other end extending through the front wall 7 in which it is suitably secured. Connected in a suitable manner with the exposed end of burner 4 is a 60

gas supply pipe 8 extending from a source of supply, not shown, and mounted in said pipe adjacent its lower end is a hand valve 9 controlling the gas flow to said burner. An auxiliary or branch gas pipe 10 leads off from supply pipe 8 and extends downwardly through end wall 7 and terminates adjacent said burner 4 in pilot light burner 11. Mounted in pipe 10 is the pilot hand control valve 12. A fire box draft door 13 is suitably mounted in wall 7 adjacent its lower edge. The side walls 14 of fire box 2 adjacent their upper edges are formed with thickened portions 15, which if desired may be hollow constituting air pockets 16.

15 Suitably mounted in firebox 2 is a hollow casing or water manifold 17, the bottom wall 18 of which is preferably arcuate and forms the roof of the fire box. The upper or top wall 19 of said manifold, while in the present instance is shown flat, 20 may be formed arcuate corresponding to wall 18 if desired, and is formed with a flange 20 adapted to seat on the upper edges of said fire box to support member 17 in proper position and form a seal connection, as clearly shown in Fig. 3 of the 25 drawings.

Wall 19 is formed with a plurality of spaced openings 21 in each of which is swedged or otherwise suitably mounted a comparatively small water circulating tube 22. Suitably mounted on 30 said tubes are a plurality of equi-spaced fin or heat distributing plates 23. An upper water manifold or header 24 is adapted to be mounted on and supported by said tubes 22 and through which latter water circulation is established between the headers 17 and 24, as will hereinafter 35 more fully appear.

While the number of water circulating tubes 22 and fin plates 23 will necessarily vary according to the size of the particular apparatus and air conditioning requirements, in the present instance the former are about 80 in number and the latter 42, and the water capacity approximately 15 gallons as compared with 150 to 200 of comparative systems now in use.

40 The water header 24 has mounted on opposite sides thereof an angle flange member 25 suitably secured by riveting, welding, or otherwise. Surmounting said header 24 is preferably a rectangular sheet metal gas fume header 26 formed at its 45 lower edges with flanges 27 adapted to seat on flanges 25 to which it is bolted or otherwise suitably secured. Said fume header 26 is formed substantially central of its length with outlet opening 28 surrounded by vertical flange 29 over 50 which is adapted to fit gas outlet or draft flue pipe 30 adapted to extend through and above the top of casing 1, as and for a purpose hereinafter more fully appearing. In order that an even draft and uniform gas and fume discharge from 55 said firebox and an increased heating result may be effected, a trio of water circulation pipes 31 of larger diameter than tube 22 are distributed in equi-spaced relation and interconnecting upper and lower water manifolds or headers 17 and 24. 60 Mounted in each of said tubes 31 is a heat and gas fume tube 32 extending through the respective water manifolds 17 and 24 and effecting communication between fire box 2 and fume header 26, so that the heated combustion gases from fire box 2 may be discharged into said fume header 26 from which they are vented by pipe 30. It will 65 thus be seen that not only an even withdrawal of the gases from the fire box is effected but the 70 gases passing through tubes 32 effect further 75

heating of the water circulating through tubes 31 as will be clear without further discussion.

Extending through the top of casing 1 through fume head 26 and through the top wall of water manifold or header 24 is a pipe 33, and on the upper end of which is suitably mounted and supported compression tank 34 for a purpose hereinafter appearing.

10 A main water supply pipe 35 with one end connected to a source of supply not shown extends downwardly and inwardly through end wall 6 and into water manifold 17 by means of which water is admitted to said generator B as will be well understood. A hand controlled valve 36 is mounted, in the present instance, at a point adjacent fume header 26, and adjacent said valve 36 is suitably mounted automatic water supply valve 37 and slightly spaced therefrom is relief valve 38 from which extends overflow or discharge pipe 39 to the sewer or other drainage system. 15

20 Mounted in supply pipe 35 adjacent its lower end is drain cock 40 by means of which drainage or emptying of the generator may be effected.

Suitably mounted in end 1 and extending within water manifold 17 is the gas valve and thermostatic control mechanism 41 connected to gas supply pipe 8 for maintaining positive temperature of the water in the generator in accordance with predetermined temperature requirements. Also suitably mounted in one end of water manifold 24 and communicating therewith is a combination altitude gauge and thermometer 42 for indicating the height of water in the system and temperature thereof. Suitably mounted on casing 1 adjacent thermostat 41 is surface thermostat 43 adapted to prevent operation of fan mechanism D when the water in the generator is cold or until a predetermined temperature thereof has been reached.

Humidifier mechanism

40 Adjacent generator B and in spaced relation with respect thereto is positioned the humidifier and air purifier unit or assembly C now to be described.

45 The humidifier and air filter mechanism C comprises a tubular water header 44 with its ends suitably supported on cleats or angle bar supports 45 riveted or otherwise suitably secured to the respective walls of casing 1 and in substantially the same horizontal plane as the bottom of manifold 24. The lower side or bottom of header 44 is formed with a plurality of equi-spaced openings 46 through which are adapted to project the upper ends of humidifier tubes 47 50 a slight distance above the bottom of said header so that when water is admitted thereto uniform flow to the various tubes will be effected. Said tubes 47 extend downwardly to a point adjacent the lower edge of casing 1 and at points 48 55 spaced from their upper ends, the sides of the tubes facing the fan unit D are cut away as at 49 so as to provide in effect a series of scrubbing tubes for a purpose more fully hereinafter appearing. The lower ends of said tubes 47 extend through the top 50' of tank 50 or like suitable receptacle formed with a drain pipe 51, and which extends beneath the entire unit C as will be clear without further discussion. Slightly 60 spaced from header 44 is a similar header 44' 65 and similar tubes 47', except that the latter tubes are positioned in staggered relation with respect to the first mentioned tubes 47.

70 Mounted adjacent header 44' slightly spaced therefrom is an angle iron member 52 with its 75

ends suitably supported on said supports 45 and formed with a plurality of semicircular openings 53, in alignment with openings 46 of header 44 in which are adapted to fit the upper ends of the similarly shaped trough like water and dirt eliminator tubes 54, the lower ends of which extend through openings 55 in top 50' similar to tubes 47. Spaced from member 52 is a member 52' formed with tubes 54' similar to elements 52 and 54 just described, except that the tubes 54' are staggered with respect to tubes 54. Tubes 54—54' are not connected with a water supply but are adapted to filter extraneous matter from the moisture laden air after passing the humidifier tubes as will directly more fully appear.

The water supply to unit C or more particularly headers 44—44' is independent to that of unit B. A water supply pipe 55 has one end connected to main supply pipe 35 above valve 36 and the other 20 is suitably connected to header 44 through casing 1, as at 56, and a branch pipe 57 similarly connects header 44' with pipe 55, whereby water is supplied to the humidifier assembly or tubes 47—47'. Said water supply is normally controlled by hydrostat 58 suitably mounted in the 25 room E or space to be heated and which controls the motor operated valve 59 mounted on supply pipe 55.

30 Electrical motor and fan assembly

The electrical motor and fan assembly or mechanism D comprises a frame 60 formed at each end with a flange 61 suitably connected to the respective sides of casing 1 spaced from the 35 humidifier unit C, and includes a semicircular spider framework 62 in which centrally thereof is suitably mounted motor 63 and on the drive shaft 64 of which is mounted fan 65.

Bolted or otherwise secured to the end 66 of 40 casing 1 is a cabinet 78 containing circuit breaker, transformer T and relay H, and a three-speed switch and capacitor 67 containing three-speed switch and coil windings. Both 67 and 78 are standard equipment. Service line 68 enters 45 cabinet 78 and the positive or hot line being connected to the transformer through circuit breaker, conductor 74, from said transformer to room thermostat 75, conductor 76, to bus bar A or connecting terminal in cabinet 78; conductor 50 80 from bus bar A to surface thermostat 43, conductor 79 to bus bar B in cabinet 78. Conductor 73 from bus bar B to the coil of relay H, and then to the other side of the transformer. The fan motor circuit comprises the conductor 55 81 from the high voltage side of the transformer to the coil windings of three-speed switch and capacitor 67, thence to motor 63, conductor 77 from motor 63, through the armature of the relay and back to the transformer, completing the fan 60 circuit. Conductor 69 connects the secondary of the transformer to the hydrostat 58, conductor 71 to solenoid or motor operated valve 59, and conductor 70 from valve 59 back to the transformer, completing the air washer circuit.

65 Casing 1 intermediate the generator mechanism B and the end of the casing adjacent its top or upper end is connected with the room space or enclosure E to be heated by air duct or register 82 adjacent one end and the opposite 70 end of the enclosure to be heated is connected by air duct 83 with a rectangular air chamber 84 positioned adjacent the floor or lower edge of casing 1 and connected thereto by the elongated air duct 85 and air circulation through the 75 apparatus and enclosure to be heated and re-

circulation thereof is effected by fan mechanism D.

While the air conditioning system and apparatus has been described in connection with supplying an enclosure with heated air in winter, it 5 is equally applicable as a cooling unit for supplying and circulating cool air through said enclosure in summer, and which may be effected by simply utilizing the generator as a cooling coil or element instead of a heating element. 10

Operation

While the operation of the device would seem to be clear from the above description, it might be well to further state that opening of hand 15 valve 36 allows automatic valve 37 to admit water to and effect filling of the generator to the proper level as indicated by altitude gauge 42 at which point the water is cut off by said automatic valve 37. Automatic valve 37 is a spring type valve 20 settable to admit water to the generator up to a predetermined pressure, that is, if ten pounds pressure equals the predetermined height of the water in the generator, said valve is set at ten pounds pressure, and when the indicator shows 25 the water has reached such height, said valve will automatically cut off the flow of water into the generator. When the pressure falls below the set pressure the valve will automatically operate to admit water until the said pressure is 30 again reached, when it will cut off as in the first instance. Assuming that the pilot is lighted, opening of hand valve 9 causes gas to flow through the thermostatic control valve mechanism 41 to burner 4 which is lighted by said pilot. 35 When the water in the generator has reached a predetermined temperature, say 140° F., thermostat 43, if the temperature in the enclosure E is approximately 2° F. below the desired temperature, say 70° F., and thermostat 75 will automatically start fan 65 to operating which will 40 continue until the desired room temperature is obtained, namely 70° F., when thermostat 75 will open the circuit to fan 65 and stop its operation until the temperature drops below 70° F., 45 at which point it will be operated as in the first instance.

With respect to the humidity control, assuming that the hydrostat 58 is set at 40% humidity, and when the humidity is below 38%, said hydrostat will open motor operated valve 59 thereby 50 allowing water to flow into manifolds 44—44' and through tubes 47—47' to be directly acted upon by the air blast from fan 65 effecting scrubbing and moistening of the air to produce the 55 desired humidity and will operate in this manner until the predetermined humidity has been attained in enclosure E, at which time hydrostat 58 will close said valve 59 and maintain the same closed until the humidity falls below 40%, or 60 other desired percent, whereupon it will open as in the first instance.

Further, whether the fan is or is not in operation, when the temperature of the water in the generator is below 160° F., thermostat 41 will 65 open and allow gas to flow to burner 4 to be ignited by pilot 11 and burn until the water reaches a temperature of approximately 180° F., at which time it will automatically cut off the flow of gas to said burner 4 and remain closed until the 70 temperature of the water in the generator drops below 160° F., whereupon it will again open and admit flow of gas to burner 4 as in the first instance.

It is further apparent that the air blast from the fan mechanism is washed by the continuous 75

flow of water passing through the humidifier tubes and the excess moisture and extraneous matter or dirt particles are extracted by adherence to the eliminator tubes as the air passes therethrough, and is heated as it passes through and between the heating tubes 22 and fin or heat distributing plates 23, said conditioned air passing upward and through upper air duct 82 to enclosure E and from said enclosure preferably at its opposite end through lower duct 83 into chamber 84 and through duct 85 into casing 1 for reconditioning as in the first instance and which recirculation of said air continues constant or intermittent according to temperature and humidity operating requirements.

From the above it is apparent that I have designed a unique air conditioning system and apparatus, simple in construction, compact in form, manufacturable and operable at a minimum of production and maintenance costs, versatile in use and efficient for the purposes intended.

Although in practice I have found that the form of my invention illustrated in the accompanying drawings and referred to in the above description as the preferred embodiment is the most efficient and practical, yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. An air conditioning apparatus comprising a casing having an inlet and an outlet, blower means within the casing for producing a circulation of air through said casing situated adjacent said inlet, a scrubbing and humidifying apparatus intercepting the path of said air, said apparatus including a series of open-faced water tubes and means for circulating water through the tubes for surface contact with the air, an eliminator disposed to the rear of the water tubes and in the path of the air leaving said tubes, said eliminator including a plurality of open-faced evaporating and cleaning tubes adapted to be impinged by the air passing through the casing, and a heating apparatus within the casing and to the rear of the eliminator to heat said tubes and the air after it has passed thereover and prior to its discharge through said outlet, and means for effecting intermittent operation of said blower means in accordance with temperature requirements.

2. An air conditioning apparatus comprising a casing having an inlet and an outlet, blower means within the casing for producing a circulation of air through said casing situated adjacent said inlet, a scrubbing and humidifying apparatus intercepting the path of said air, said apparatus including a series of open-faced water tubes and

means for circulating water through the tubes for surface contact with the air, an eliminator disposed to the rear of the water tubes and in the path of the air leaving said tubes, said eliminator including a plurality of open-faced evaporating and cleaning tubes adapted to be impinged by the air passing through the casing, and a heating apparatus within the casing and to the rear of the eliminator to heat said tubes and the air after it has passed thereover and prior to its discharge through said outlet, means for respectively controlling said blower and heating apparatus in accordance with temperature requirements and means for controlling said water circulating means in accordance with humidity requirements.

3. An air conditioning apparatus comprising a casing having an inlet and an outlet, blower means within the casing for producing a circulation of air through said casing situated adjacent said inlet, a scrubbing and humidifying apparatus intercepting the path of said air, said apparatus including a series of open-faced water tubes and means for circulating water through the tubes for surface contact with the air, an eliminator disposed to the rear of the water tubes and in the path of the air leaving said tubes, said eliminator including a plurality of open-faced evaporating and cleaning tubes adapted to be impinged by the air passing through the casing, and a heating apparatus within the casing and to the rear of the eliminator to heat said tubes, said heating apparatus including a series of vertically spaced plates extending transversely of the casing and forming series of superimposed heating passages, a plurality of hot water circulating tubes in connection with the plates to heat the latter and means for controlling the heating apparatus in accordance with temperature requirements.

4. An air conditioning apparatus comprising a casing having an inlet and an outlet, blower means within the casing for producing a circulation of air through said casing situated adjacent said inlet, a scrubbing and humidifying apparatus intercepting the path of said air, said apparatus including a series of open-faced water tubes and means for circulating water through the tubes for surface contact with the air, an eliminator disposed to the rear of the water tubes and in the path of the air leaving said tubes, said eliminator including a plurality of evaporating and cleaning plates adapted to be impinged by the air passing through the casing, and a heating apparatus within the casing and to the rear of the eliminator to heat said evaporating and cleaning plates and the air after it has passed thereover and prior to its discharge through said outlet, means for controlling said blower and heating apparatus in accordance with temperature requirements and means for controlling said water circulating means in accordance with humidity requirements.

ROBERT A. BRAND.
